UNITED STATES PATENT OFFICE

97,428

DESIGN FOR A MEAT TENDERER OR SUET CUTTER ATTACHMENT FOR MALLETS

Quincy Beltram, Newark, N. J., assignor to International Edge Tool Co. Inc., Newark, N. J., a corporation of New Jersey

Application August 3, 1935, Serial No. 57,930
In Canada April 20, 1935

Term of patent 7 years

To all whom it may concern:

Be it known that I, Quincy Beltram, a citizen of the United States, residing at Newark, in the county of Essex and State of New Jersey, have invented a new, original, and ornamental Design for a Meat Tenderer or Suet Cutter Attachment for Mallets, of which the following is a specification, reference being had to the accompanying drawing, forming a part thereof; of which

Figure 1 of the drawing is an edge view of the attachment showing my new design.

Figure 2 is a bottom plan view of the attachment.

Figure 3 is a perspective view of the attachment.

The design is characterized by a rectangular plate having angular corners, rows of teeth projecting from one side of the plate, and a circular curb projecting from the opposite side and provided with ears attachable to a mallet head. The diameter of the curb is greater than one of the sides of the plate, so that portions of the curb overhang portions of the margin of the plate between the angular corners of the latter.

I claim:

The ornamental design for a meat tenderer or suet cutter attachment for mallets as shown and described.

QUINCY BELTRAM.
